SANDER

Charles A. Campbell, Watertown, N. Y., assignor
to The New York Air Brake Company, a cor-
poration of New Jersey

Application October 6, 1938, Serial No. 233,679

11 Claims. (Cl. 291—3)

This invention relates to sanding devices for high speed trains, and particularly to means for shortening the interval between the actuation of the device which causes sanding, and the actual initiation of a sanding operation at the rail.

Probably the greatest cause of time lag is occasioned by location of the sand trap at a point remote from the point of sand delivery. It has heretofore been proposed to mount gravity sand boxes directly on the truck and deliver the sand by gravity to the rail in front of the wheels, but the necessary size of the sand box makes the scheme undesirable even in cars of old design, and impracticable on modern high speed streamlined cars in which the body is low on the trucks, the four-wheel trucks commonly used are equipped with four brake cylinders and such complicated spring plank and link mechanism that there is little available space on the truck.

The present invention solves the problem of short path delivery by mounting on the truck small sand traps, each with a local sand storage chamber only large enough to contain the charge of sand for a single timed sanding operation. This is feasible because modern sanding devices commonly include a timing device which causes them to deliver sand for the duration of an emergency stop. Such sanding systems also include additional manually operable devices for sanding at will, but the duration of such sanding operations is normally shorter than the duration of the timed sanding above described. Consequently, a local storage chamber which will provide for a single automatic timed operation will meet the requirements of the service.

To permit the use of these small local chambers, I mount a sand box of substantial size on the car body and provide flexible tubular supply connections from the main sanding box to the local chambers on the trucks. With these is used a measuring feed mechanism which, as an incident to each sanding operation, will supply, from the main sand box to each local chamber, a charge of sand just sufficient to refill the local chambers.

This scheme is workable despite the limited space available on high speed streamlined cars. It can be arranged to sand in front of the leading wheels of the truck only or in front of all wheels of the truck. The problem is simplified somewhat by the fact that such trains operate at high speed in one direction only. For this reason sanding for a backing, except on the propelling unit, is a matter of minor importance.

The invention makes use of an adaptation of the intercepting valve mechanism described and claimed in the application of Campbell and Safford, Serial No. 149,193, filed June 21, 1937. Consequently, no broad claim to this intercepting valve mechanism 5 per se is made in the present application.

Systems of the type above outlined are capable of embodiment in specifically different forms. The details of each installation depend on structural aspects of the train to which it is applied. Hence in this specification the description of the invention will be based on a general schematic showing sufficient to permit explanation of the operative principles of the invention without even implied limitation to the specific arrangement shown.

It is simpler to describe sanding for the front wheels of the truck only. Since the provision of additional means for sanding other wheels on the same truck involves mere duplication of trap and local chamber units, only mechanical skill is required to adapt the scheme to more wheels or even all wheels on the train. Similarly, it is immaterial whether the train be of the articulated type or of the type in which each car is complete in itself, or involve some combination of these two schemes as in the case of certain streamlined trains operating in the West. These differences affect the location of the main sand boxes, the number of units, and similar details, but the invention in its basic principles is applicable with only slight variation to meet requirements imposed by the particular construction of the train.

The invention will now be described with reference to the accompanying drawings, in which:

Fig. 1 is a piping diagram of a system having a motor car and one trailer. Only two sand traps are shown on each of the two cars, each car being fitted with a single sand box to supply sand to the local chambers of each of the two traps on that car. The purpose is to show a plurality of sanders with local reservoirs and still keep the number at a practicable minimum to simplify the description. A larger number of sanders would ordinarily be used and each would be equipped with a local reservoir and with means for feeding from the main sand box. In this view pneumatic control is indicated on the motor car with electric control on the trailer, the two schemes being approximate equivalents except from the standpoint of speed of operation.

Fig. 2 is a diagrammatic section of the sander control mechanism carried on the motor car.

Fig. 3 is a similar sectional diagram of the controlled mechanism carried on the motor car.

Note.—By assembling Fig. 2 immediately above Fig. 3 a complete diagram of the sanding apparatus for the motor car corresponding to the left-hand portion of Fig. 1 is produced.

Fig. 4 is a sectional view of the magnet valve and piston operated valve controlled thereby which are mounted on the trailer and used to operate the sander. The sand box, sand traps, and local chambers on the trailer are identical in structure with the showing in Fig. 3.

Fig. 5 is a section on the line 5—5 of Fig. 3 and shows the construction of the measuring chamber where the sand box delivers to two sand traps.

Fig. 6 is a horizontal section through a local sand chamber on the plane of the sand inlet.

Referring first to Fig. 1, 8 represents an engineers' brake valve assumed to have a sanding port connected to the pipe 7. When the engineers' brake valve is moved to emergency position the sanding port admits air at main reservoir pressure to pipe 7, and this is caused to operate the sanding mechanism as hereinafter explained.

8 indicates the body of a sander valve which may be brought into action by the operation of the engineers' brake valve as just described. It may be caused to sand for a definite time interval by depressing the button 9, and may be caused to sand for any shorter period by depressing the button 11, sanding continuing while the button 11 is held depressed.

The timing reservoir 12 determines the duration of sanding if the valve 8 is operated either by movement of the engineers' brake valve 6 to emergency position or by pressing the button 9, the duration of sanding being the same in either case. An air reservoir 13 supplies air under pressure for the sanding operation. This may be the main reservoir of the brake system or any other suitable source of air under sufficient pressure. The sander valve 8 is connected by the branch pipe 14 with two devices for controlling the sander. The first of these is a pneumatic relay 15 which in the example illustrated controls the supply of sanding air to the sander mechanism on the leading vehicle. The second of these devices is a pressure-operated switch generally indicated by the numeral 16 and controlling a train circuit for causing sanding on the trailers.

Switch 16 comprises a piston 17, normally held down by a spring 18 and subject on its lower side to the pressure in pipe 14. When the piston is forced up by pressure developed in pipe 14, a contactor 19 closes a sander circuit comprising wires 21, 22, 23, normally closed switch 24, a source of electric current typified by battery 25 through the actuating winding 26 of the magnet valve indicated generally at 27. This magnet valve, when its winding is excited, admits pressure fluid to a piston-operated sander valve generally indicated at 28, and opens the same admitting actuating air to the sanding units on the first trailer. Where more than one trailer is used, as is commonly the case, the windings 26 of the magnet valves for the various trailers are connected in parallel between wires 21 and 23 so that all the magnet valves 27 operate simultaneously.

The sander valve 8 is manufactured in substantial accordance with the U. S. Patent to Campbell, No. 2,035,533 issued March 31, 1936, and is illustrated in section in Fig. 2. Since the structure is known and is not here claimed, a brief statement of its operation will suffice. The pipe 7 leading from the engineers' brake valve 6 supplies air

above the piston 31 and will force that piston downward producing exactly the same effect that is produced by forcing the knob 9 downward. It causes movement of balanced piston valve 32 to its lowermost position against the resistance of spring 33. In its uppermost position main reservoir air supplied through the pipe 34 passes the reduced middle portion of valve 32 and flows through the pipe 35 to the timing reservoir 12, charging it to supply pressure. When the valve 10 is shifted by button 9 or by piston 31, the reduced portion of the valve connects reservoir 12 with the space above piston 36 so that valve 32 is moved all the way down, blanking supply connection 34 and connecting pipe 14 and exhaust choke 15 with reservoir 12.

The effect of such motion, therefore, is to develop sufficient downward air pressure on piston 36 to hold the valve in its lowermost position until the choke 37 has bled reservoir 12 to such a low pressure that spring 33 can restore the valve 32 to its initial position. The parts are so designed that the valve 32 will stay in its lowermost position for a period slightly longer than the duration of an emergency stop.

When the valve is restored to its uppermost position, port 14 is blanked and choke 37 immediately vents pipe 14. It will be understood that the existence of substantial pressure in pipe 14 causes sanding on the trailers by closing the switch 19 and causes sanding on the motor car by opening the pneumatic relay 15.

In order to secure sanding at will, when the valve 32 is in its uppermost or normal position, a poppet valve 38 is provided. This valve is unseated by the button 11 against resistance of a spring 39, and when opened, connects the supply line 34 via the reduced portion of the valve 32 with the port 41 which leads to the connection 14, but not to the space above the piston 36. Consequently, pressure will be developed in pipe 14 so long as the button 11 is held depressed and will be dissipated rapidly through choke 37 when the button 11 is released and the valve 38 closed.

The relay 15, which is shown in section in Fig. 2, comprises a cylinder 42 in which is a piston 43. The pipe 14 communicates with the space below piston 43. The space above the piston communicates with the pipe 44 which delivers sanding air to the sanding mechanism, that is, to the mechanism which delivers sand from the sand box to the local reservoirs on the traps and also to the air jets and intercepting valves forming parts of the traps. The piston 43 has a stem 45, guided at 46 and carrying a plunger 47 which is urged outward by the coil compression spring 48 housed in the stem. When the piston 43 is forced upward it unseats a poppet valve 50 and admits to the pipe 44 main reservoir air arriving through the pipe 49. A filter 51 is interposed in the path of flow. Valve 50 is urged in a seating direction by the coil compression spring 52 and also by main reservoir air pressure which acts on the valve in a closing direction.

Turning now to Fig. 4, it will be observed that the winding 26, which is energized when the switch 16 closes, operates a double-beat valve, that is, a normally open exhaust controlling valve 53, and a normally closed supply controlling valve 54. The double-beat valve is biased as stated by a coil compression spring 55 so that normally the pipe 56 is vented to atmosphere, but when the winding 26 is energized, the valve 53 is closed and the valve 54 is opened, so that air from the supply reservoir coming by way of the 75

train pipe 57 which is connected from vehicle to vehicle as indicated at 58, is admitted through a branch pipe 59 to the pipe 56.

The pipe 56 is connected to the piston-operated valve generally indicated at 28 in Fig. 1 and shown in section in Fig. 4. Air pressure, when admitted, depresses the piston 61 and opens the poppet valve 62 against the resistance of the closing spring 63. The supply pipe 57 supplies air to the valve 62 by way of the branch pipe 64 so that the effect of opening the valve 62 is to admit air at supply pressure to two pipes 65a and 66a. These are identical in arrangement and function with two branches of pipe 44, which consequently are designated on Fig. 1 as 65 and 66.

The arrangement above shown is such that if the engineers' brake valve is moved to emergency position, or if the button 9 is depressed, the pipes 65 and 66 on the motor car and the pipes 65a and 66a on the trailer will be subjected continuously to supply pressure for a definite time period. If the button 11 is depressed, the pipe named will be subjected to supply pressure as long as the button is depressed. However, since the sand trap holds a charge of sand only sufficient to last for the duration of an emergency stop, continuous sanding cannot last longer. Release of button 11 will, however, cause prompt sand recharge.

Upon the termination of such a sanding operation and dissipation of pressure in the pipes 65 and 66, the sanding mechanism will automatically recharge itself and become almost instantaneously ready for an ensuing sanding operation. The operation of this part of the mechanism can best be described with reference to Fig. 3.

Fig. 3 shows simply the unit on the leading car as clearly indicated in Fig. 1. This unit is duplicated on the single trailer there shown and would be duplicated on any additional trailers in the train. The main sand box 67 for a group of sand traps is intended to be mounted on any suitable support, usually the car body, and may be quite remote from the sand traps 68 which it feeds and which are intended to be mounted very close to the points of sanding. In Fig. 3 only two such traps are shown and these are supposed to sand in front of the forward wheels of the forward truck of the train. In such event they can conveniently be mounted on the forward corners of the forward truck, but it must be clearly understood that a single sand box 67 can furnish sand to any reasonable number of sand traps. That is, it may supply sand to any reasonable number of sanders on a single truck, or if the car has more than one truck, it may furnish sand to any desired number of sanders on the various trucks. In other words, the sand box 67 is simply a reservoir from which sand is forcibly fed to local sanding chambers associated with a plurality of sand traps.

The sand box 67 has a removable cover 69 clamped in place by a wing-nut as shown and provided with a breather filter 71. The bottom of the sand box is provided with a jacket space 72 through which a heating fluid may be circulated by way of the pipe connections 70. Mounted below the discharge opening 73 of the sand box 67 is a body 74 which houses the intercepting valve and the measuring chambers. The structure of these measuring chambers is clearly indicated in Fig. 5 in which there are two cham-

bers 75 and 76 of equal volume separated by a divider partition 77.

Fig. 5 shows two chambers because Fig. 3 shows two sand traps. The number of chambers will correspond to the number of traps to be fed.

The discharge opening 73 communicates with the measuring chambers 75 and 76 through a distensible tube of rubber or like material indicated at 78 and sustained by a bushing 79 which engages the upper and lower flanged ends of the tube and leaves the middle portion of the tube laterally unstained by affording the chamber or channel 81 around the same. Mounted immediately below the lower end of the tube 78 and arranged to seat against the lower end thereof, is the intercepting valve. This comprises a fixed tubular stem 82 with the distensible bulb 83 of rubber-like material over which is mounted the inverted cup-shaped valve element 84. When the bulb 83 is inflated, the valve 84 seats on the lower end of the tube 78, which as stated is supported by the bushing 79. However, sand in the tube 78, if it tends to arch and resist upward flow, will simply spread the tube 78 into the space 81 so that the valve 84 may close tightly. This is important as it not only prevents dribbling of the sand, but insures hermetic closing of the measuring chambers during the sand transferring operation.

The pipe 66 leads to the chamber 85 with which the bore of stem 82 is in open communication, so that when pipe 66 is under pressure, the valve 84 is closed. Chamber 85 also communicates with the bores of two nozzles 86 which are directed across the lower portions of the two measuring chambers 75 and 76 and discharging into ejector tubes 87, one in each chamber, which are individually connected by pipes 88 and 89 with the local sand chambers 91 which are associated with the respective sand traps 68.

Thus, when the pipe 66 is not under pressure, the valve 84 is open, and sand flows down through the tube 78 and fills both the chambers 75 and 76 full of sand. When air under pressure is admitted to pipe 66, the valve 84 will close, isolating the measuring chambers from the sand box and the nozzles 86 will begin to eject sand from the corresponding measuring chambers and deliver it to the corresponding local chambers 91 for the various sanders.

It will be helpful to observe at this point that the capacity of the measuring chambers 75 and 76 (there being one such chamber for each trap to be fed) corresponds with the capacity of the local sand chambers 91 to which they respectively deliver, and that the local sand chambers, at the time such delivery starts, will be empty and will be isolated from their respective sand traps. Consequently, during each sanding operation, the local chambers 91 receive a measured charge for the next succeeding sanding operation, retain that charge until sanding is completed, and then empty themselves into the sand traps so that the apparatus is again conditioned for a measured sanding operation.

Each local sand chamber 91 is mounted on top of the corresponding sand trap 68 and has at its top a vent opening protected by a depending skirt 92 which defines a centrifugal chamber into which the sand is projected tangentially, as indicated at 90 (Fig. 6). The vent opening is further protected by a removably mounted sand-arresting filter and rubber protecting cap designed to prevent the entrance of moisture and the escape of sand. This unit comprises a supporting screen 73

or perforated plate 93, a fabric filter 94, a second screen or perforated plate 95, a perforated retaining spider 96, a cup-shaped rubber valve element 97 having a downward extending peripheral flange, a washer 98, and a retaining screw 99 which is threaded into the hub of a spider 101 cast integrally with the body of the chamber 91.

The discharge opening 102 delivers into a tube 103 sustained by an insert 104. The parts 103 and 104 are structurally and functionally similar to the parts 78 and 79 already described. There is also an intercepting valve having a stem 105, bulb head 106, and valve element 107, which are structurally and functionally similar to parts 82, 15 83 and 84 already described.

The line 65 leads directly to the bore of the tubular stem 105, and since the pipes 65 and 66 are subjected to pressure simultaneously, the valve 107 will close simultaneously with the closure of the valve 84. Thus, between sanding operations the valve 107 permits sand to flow freely from the local chamber 91 into the body of the trap 68. Chamber 91 is so dimensioned as to hold the complete charge of the sand trap so that 25 at the termination of a sanding operation when the valve 107 opens, all the sand will flow from the sander 91 into the trap 68.

At the commencement of the sanding operation the valve 107 closes so that while sand is being 30 fed from the measuring chambers 75, or 76 as the case may be, into the corresponding chamber 91, that chamber is isolated from the sand trap. The pipe 65 is in free and constant communication with the stirring nozzle 108 which discharges under the baffle 109 and in a direction away from the crest 111 over which sand must flow to enter the sand conducting pipe 112. This pipe 112 terminates in a distensible rubber nozzle 113 which is directed to the angle between the wheel and 35 the rail. A nozzle 114, aligned with the stem 105 of the intercepting valve sends a jet of air down the pipe 112, and like the nozzle 108 is in constantly free communication with the pipe 65.

It should be observed further that since the 40 valve 107 seals air-tight, the trap operates under high pressure.

It should also be observed that when the pipe 45 65 first delivers pressure fluid to the trap, a clean-out blast is discharged at 115 across the top of trap 68 and simultaneously through 116 to the entrance end of the pipe 112. The purpose of this is to develop equal pressures above and below partition 109 so that the charge of sand will not be blown out of the trap.

The clean-out blast through openings 115 and 50 116 is only temporary and is controlled by an intercepting diaphragm 117 which is urged against a seat 118 by a spring 119. The seat 118 controls flow to the passage 121 which leads to the passages 115 and 116. From the pipe 65 flow is by 55 way of a port 122 to the space around the seat 118. The first effect is to over-power the spring 119 and force the diaphragm 117 back, but a choke 123 leads air from the port 122 to the space behind the diaphragm 117 so that after a short time interval air pressures on the diaphragm 117 equalize and spring 119 seals the diaphragm on the seat 118. Hence, the initial 60 blast through passages 115 and 116 occurs only for a short time, determined by the relative capacity of the choke 123 and the chamber behind the diaphragm 117. The location of the timing valve directly in the trap accelerates the delivery of the clean-out blast and hence contributes to 65 rapid initiation of sanding.

The general operation of the system has already been described and a brief summary will suffice. Timed sanding is initiated by moving the engineer's brake valve 6 to emergency position or by depressing the button 9. Sanding at will, that is, without the timing feature, may be brought about by holding down the button 11 and may be had as long as desired with brief interruption to replenish the sand in the traps in the rare case that sanding for a very long period is desired. On the leading car the pneumatic relay 15 puts the pipes 65 and 66 under pressure delivered directly from the supply reservoir 13. On the trailer vehicle, or vehicles, the pipes 65a and 66a are supplied with air from the same source 15 by the operation of the magnet valve 27 and the piston-operated valve 28. The duration of air flow during timed sanding on the leading car and on the trailers is the same. Electric actuation is faster than pneumatic actuation and is therefore preferred, particularly for the trailers, but pneumatic actuation is possible and is shown on the leading car to which it is well adapted because the distance is so short that pneumatic actuation is sufficiently rapid. 25

Trailer units can be cut out by opening the switch 24. During each sanding operation the sand box 67 is sealed from the measuring chambers 75, 76, the local chambers 91 are sealed from the corresponding traps 68, and the nozzles 86, 30 35 are active to deliver measured charges of sand from the respective measuring chambers to the local chambers 91. Timed operation of jets 108 and 114 discharges all sand from the respective sand traps through the corresponding nozzles 113, 35 so that the sand traps empty. At the same time measured charges of sand are transferred from the measuring chambers 75, 76 to the corresponding local chambers 91.

At the termination of the sanding operation the 40 supply of air to the pipes 65, 66, 65a and 66a will be simultaneously terminated. The pressure in these pipes will be immediately dissipated by flow through the nozzles 86, 108 and 114. Consequently, the valve 107 will open delivering the 45 accumulated charges from the local chambers to the corresponding sand traps, and the valve 84 will open permitting new charges to flow from the main sand box and fill the measuring chamber. 50

In this way, and within a few seconds of the termination of sanding, the system is recharged with sand for another timed sanding operation.

The rubber nozzles 113 are distensible to free ice and mud under the shock discharge of the 55 initial clean-cut blast, but this feature is a part of the subject matter of the prior application above identified and is not here claimed.

As has already been explained, the embodiment here illustrated has been chosen primarily to permit a simple disclosure of the invention, and in actual service various other arrangement are possible and contemplated. Consequently, the disclosure above made should be considered as 60 illustrative and not limiting. 65

What is claimed is:

1. The combination of a sand trap located adjacent the point of sanding and adapted to retain when inactive a charge of sand for a single sanding operation; a source of sand located at 70 a relatively remote point from the point of sanding; a local chamber adjacent the sand trap adapted to accumulate a charge of sand sufficient for one sanding operation; pneumatic means for transferring sand from said source to 75

said chamber; means operable to cause said sander to sand and to cause said transferring means to operate simultaneously; and means rendered effective by the termination of operation of the last named means to cause delivery of sand from said local chamber to said sand trap.

2. The combination of a sand trap of the pneumatic jet type located adjacent the point of sanding and adapted to retain when inactive a charge of sand for a single sanding operation; a source of sand located at a point relatively remote from the point of sanding; a local chamber adjacent the sand trap, adapted to accumulate a charge of sand sufficient for a single sanding operation; pneumatic means for transferring sand from said source to said chamber; means operable to supply air under pressure simultaneously to the jets of said trap and to said transferring means to cause the trap to sand and cause transfer of sand to said local chamber; and means rendered effective by termination of said supply of air to deliver sand from said local chamber to said trap.

3. The combination of a sand trap of the pneumatic jet type, located adjacent the point of sanding and adapted to retain a charge of sand for a single sanding operation; a source of sand located at a point relatively remote from the point of sanding; a local chamber adjacent said sand trap and adapted to accumulate a charge of sand sufficient for a single sanding operation; normally open intercepting valve means between said chamber and trap and adapted to be closed when subjected to pneumatic pressure; pneumatic conveying means for transferring sand from said source to said chamber; and means operable to supply air under pressure simultaneously to said intercepting valve, conveying means and the jets of said sander, and alternatively to cut off such supply.

4. The combination of a sand trap having a chamber adapted to retain a charge of sand for one sanding, a crest over which the sand must rise to discharge and air jet means to flow the sand over the crest and propel it to the point of sanding; a local storage chamber normally in communication with the chamber of the trap and arranged to deliver sand thereto by gravity flow; an intercepting mechanism adapted to seal the communication between said chambers and comprising a valve, pressure motor means for closing the valve and means biasing the valve to open; a source of sand; a pneumatic jet conveyor for feeding sand from said source to said storage chamber; and means for supplying air under pressure to the jets of said trap and conveyor and to the motor of said intercepting valve, and alternatively to cut off said supply, and cause the motor to be vented.

5. The combination of a sand trap of the pneumatic jet type located adjacent the point of sanding and adapted to retain a charge of sand for a single sanding operation, a local storage chamber normally in communication with said trap and arranged to deliver sand to the trap by gravity flow, said local chamber being vented to atmosphere; a sand retaining filter mounted in said vent to prevent the escape of sand; a freely outward opening valve for resisting the entrance of water into said chamber; an intercepting mechanism adapted to seal the communication between the local storage chamber and the sand trap and comprising a valve, pressure motor means for closing the valve and means for biasing the valve in an opening direction; a source

of sand; a pneumatic jet conveyor for feeding sand from said source to said storage chamber; and means for supplying air under pressure to the jets of said trap and conveyor and to the motor of said intercepting valve, and alternatively to cut off said supply and cause the motor to be vented.

6. The combination of a sand trap of the pneumatic jet type located adjacent the point of sanding and adapted to retain a charge of sand for a single sanding operation; a local storage chamber normally in communication with the chamber of the trap and arranged to deliver sand thereto by gravity flow, said chamber being of generally circular configuration when viewed from above and having at its top an air vent surrounded by a depending skirt; an intercepting mechanism adapted to seal the communication between said chamber and trap comprising a valve, pressure motor means for closing the valve and means biasing the valve in an opening direction; a source of sand; a pneumatic jet conveyor for feeding sand from said source to said storage chamber, the parts being so arranged that the sand enters the storage chamber tangentially and in a portion outside said depending skirt, whereby centrifugal separation of sand and air is afforded; and means for supplying air under pressure to the jets of said trap and conveyor and to the motor of said intercepting valve, and alternatively to cut off said supply and cause the motor to be vented.

7. In a pneumatic sanding system the combination of a source of air under pressure; operator-operated means for controlling the supply of air from said source; a main source of sand; normally open pneumatically closed intercepting valve means for closing the discharge of sand from said source; at least one unit comprising a chamber fed by flow past said intercepting valve means and adapted to contain sand for at least one sanding operation, jet means for transferring sand from said chamber, a local chamber to which said jet means delivers, a sand trap adapted to contain a charge of sand for a single sanding operation arranged to be fed by said local chamber and including jet means for discharging sand from said trap to the point of use in the sanding operation, a normally open pneumatically closed intercepting valve means for isolating said sand trap from its local chamber; and connections whereby said operator-operated means admits air under pressure simultaneously to both said intercepting valve means and to the jet means of said sand trap, and transferring means and of said sand trap, and alternatively vents the same.

8. The combination defined in claim 7 in which the intercepting valves are of the poppet type and coact with resilient seats provided with distensible approach tubes whereby hermetic sealing is assured despite resistance offered to tight closure by the approaching sand.

9. Means for delivering sand from a source to a point of sanding comprising two air operated jet conveyors arranged in tandem at considerable distance apart, the jet mechanism of each conveyor including means for storing, when the jets are inactive, a measured charge of sand which the jets when active progressively discharge, the first of said storing means being arranged to be fed with sand by gravity flow from a source; means forming a local storage chamber to which the first conveyor delivers, said local chamber being arranged to feed the storing means of the

second conveyor by gravity flow; means for supplying and cutting off air under pressure to the jets of said conveyors; and means rendered active as an incident to the supply of air to the jets to cut off feed to the storage means of the conveyors.

10. The combination of a sander having a chamber for retaining a charge of sand and jet mechanism for propelling sand from said chamber; a source of sand; a measuring chamber to which said source delivers; jet means for propelling sand from said measuring chamber; a local storage chamber to which the last named jet means delivers, said local chamber being arranged normally to deliver its charge of sand to said trap; means for supplying air under pressure to said jet means; and means rendered active as an incident to the supply of air to said jet means to isolate said measuring means from said source and said trap from said storage chamber.

11. The combination of a sand trap including a sand propelling jet nozzle and means for retaining a supply of sand adjacent said nozzle whereby sanding will commence and continue at least for a limited period upon the supply of pressure fluid to said nozzle and will terminate at least as early as the termination of said fluid supply; a sand feeder connected to feed to said trap and including a jet nozzle and means for retaining a supply of sand adjacent said nozzle whereby feeding will commence and continue at least for a limited period upon supply of pressure fluid to said nozzle and terminate at least as early as the termination of said fluid supply; a source of sand connected to supply sand to said feeder; and means for supplying pressure fluid to said nozzles substantially simultaneously, and for terminating said supply.

CHARLES A. CAMPBELL.

20.
